UNITED STATES PATENT OFFICE.

IRVIN D. LENGEL, OF READING, PENNSYLVANIA, ASSIGNOR TO KNOILL MANUFACTURING CO., OF READING, PENNSYLVANIA, A CORPORATION OF PENNSYLVANIA.

MULTIPLE-TUB WASHING MACHINE.

Application filed July 7, 1921. Serial No. 482,888.

To all whom it may concern:

Be it known that I, IRVIN D. LENGEL, a citizen of the United States, residing at Reading, in the county of Berks and State of Pennsylvania, have invented certain new and useful Improvements in Multiple-Tub Washing Machines, of which the following is a specification.

My invention relates particularly to washing machines adapted for domestic use; and my general object is to provide for cooperatively employing washing and wringing mechanism having driving means common to both, in connection with a series of tubs variably positioned jointly relative thereto so as to enable the advantageous effecting of successive washing and rinsing operations in determined tubs simultaneously with wringing operations as required. The complete invention is fully described in connection with the accompanying drawings illustrating a preferred embodiment thereof, and the novel features are clearly defined in the claims.

Figure 1, is a partly sectional elevation of a structure embodying the complete invention; the section being taken mainly on the line 1-1 of Figure 2, and certain of the parts being omitted or only sufficiently indicated to make clear the cooperative arrangement.

Figure 2, is a corresponding plan view; the series of jointly-adjusted tubs being indicated without showing of the carrier-arm hub connection.

Figure 3, is a plan view of the wringer arm, with a partial section on the line 3-3 of Figure 1 indicating the means provided for locking the same in rigidly adjusted position on the standard.

Figure 4, is a partial elevation at right angles to Figure 1, showing the agitator bearing bracket in cross-section on the line 4-4 of Figure 1.

Figure 5, shows a plan view of the tub-carrier hub and portions of connected spoke-arms.

Figure 6, is a plan view of the sectional tub cover employed; the middle section shown being adapted to be carried by the swinging agitator arm without the separately applied side sections.

As shown in the drawings the complete structure is made up of separate parts so as 55 to permit of conveniently disassembling the

same for compact storage or shipment. The supporting standard shown, comprises a basic tubing 10 to which is fixedly secured a supporting sleeve 11 having supporting legs 12 fastened thereto: said sleeve 11 also serving to support a rotary tub-carrier hub 15, having a series of spoke-arms 16 removably secured thereto, and each adapted to carry one of a circular series of tubs 17. A motor base-plate 18 is fixed to the tubing 10 above the tub-carrier device, and the standard is continued by a motor-housing casting 20, encircling an electric motor 21 fixed to the plate 18 as indicated and having a top tubing extension 10^a.

A wringer-carrier arm 25, having spaced hub bands 26 rotatably mounted upon the standard portion 10^a, and carried by a toothed collar 28 fixed to the latter between said bands, is provided with a handled locking device 29 pivoted to hub ears 30 so as to engage any determined tooth of said collar to lock the arm in any rotatively adjusted position upon the standard. A wringer 32 having a driven roll 34 and a roll-discharge 80 apron 33 arrangeable to discharge in either direction, is fixed to said arm 25.

Fixed to the top of the standard is an agitator bearing bracket 40 in which is mounted a horizontal drive shaft 41 having a fixed 85 belt wheel 41^a adapted to be driven by the motor shaft 21^a. This bracket is shaped to form a protecting casing for said drive shaft 41; and its connection to the standard is effected by means of a cupped end portion 40^a 90 which is arranged to enclose a worm screw 41^b fixed to one end of drive shaft 40, and a meshing gear 45 fixed to a vertically mounted gear axle 46. The bracket portion 40^a is shown as rigidly secured to the standard by means of a fitted boss 40^b thereon extending into the latter, and as being formed separately from the main bracket portion 40, which however is rigidly connected thereto.

Rotatably mounted upon a cover plate 40^c 100 on the cupped bracket portion 40^a, is a wringer-gear casing 50, in which is mounted a horizontal coupling shaft 51 arranged in the plane of the wringer roll 34 and adapted to be suitably coupled to the latter. This coupling shaft 51 is provided with spaced-apart bevel gears 52, 53 arranged in mesh with a gear wheel 54 fixed to the vertical gear axle 46; and also with an intermediate clutch sleeve 54^a, which is shown in disen-

gaged position in Figure 11 but may be moved by a suitable lever 54^b so as to cause rotation of the wringer roll in either direction as desired.

- 5 Swingably mounted upon the end of the fixed bracket 40 is an agitator arm 60, pivoting at the axis of the drive shaft 41 and having an agitator shaft 61 mounted at the free end thereof so as to carry the attached agitator device 62 into a positioned tub when the arm is lowered in its vertical swinging plane. Oscillating motion is imparted to this agitator device from the drive shaft 41, by means of a worm screw 63 on the extending 10 portion of said shaft upon which the arm 60 is pivotably mounted as indicated; said worm being arranged in constant mesh with a worm wheel 64 mounted at 65 on the arm 60, and said wheel having a crank arm 66 carrying a rack-bar 67 held in engagement with a toothed wheel 68 on the agitator shaft 61 substantially as heretofore employed; but provision being made in usual manner for loosening or tightening said worm screw 63 upon the drive shaft by means of a clutch lever 70, so as to make the rotation of the 15 drive shaft 41 effective or ineffective upon the agitator as may be desired.

In order to provide for convenient access 30 to any tub when the agitator is in place therein, I employ a sectional tub cover or lid; which, as shown in Figure 6, is preferably formed in three sections so that the middle one, 72, may be carried upon the agitator shaft 61 and thus be raised and lowered with the swinging agitator arm 60, while the side sections 72^a and 72^b may be independently placed or removed as desired; the middle section 72 being thus adapted to 35 carry the weight of the lowered agitator mechanism, independently of the separate lid sections 72^a and 72^b and also of any stops provided on the fixed standard-bracket 40 for positively limiting the swing of the agitator arm. Each of the tub-carrying spoke- 40 arms 16 is independently attachable to the rotary hub 15 by means of headed projections 16^a engageable in vertical peripheral recesses 15^a of the hub so as to rigidly connect it to the latter while permitting of its 45 ready removal when desired.

It will be readily understood that the horizontal drive shaft 41 may be continuously rotated, and be made effective in driving 50 either the agitator or the wringer, or both, as desired; any one of the series of tubs provided being placed in operative relation to the agitator as desired and so held by an arm-engaging catch 80, and the relation of 55 the wringer to any determined tub or tubs being independently adjustable while in operative connection with the common drive shaft; so that the several operations of filling, washing, rinsing and wringing may be 60 carried on simultaneously or separately in 65

the several tubs in the most advantageous way. The complete machine provides a well-balanced structure, having the operating parts neatly encased for safety and efficient lubrication, and always conveniently operable while at the same time adapted to be readily disassembled for compact storage.

What I claim is:

1. A washing machine comprising a central standard having a bearing bracket fixed thereto, a radially arranged agitator frame on said bracket swingable in a vertical plane thereon and carrying a rotative agitator device, a drive shaft horizontally mounted in said bracket, an agitator drive mechanism 75 carried by said swingable frame and operatively engageable with said drive shaft, and means for supporting a circular series of tubs in determined operative relation to said agitator device.

2. A washing machine comprising a central standard having a bearing bracket fixed thereto, a radially arranged agitator frame on said bracket swingable in a vertical plane thereon and carrying a rotative agitator device, a drive shaft horizontally mounted in said bracket, an agitator drive mechanism carried by said swingable frame and operatively engageable with said drive shaft, and means for supporting a circular series of 90 tubs in determined operative relation to said agitator device; said swingable agitator frame carrying a tub-cover section adapted to form a support therefor upon a tub and a partial cover only for the latter.

3. A washing machine comprising a central standard having a fixed bearing-bracket with a horizontal drive shaft mounted therein and an agitator mechanism swingable thereon in operative connection with said drive shaft; a motor fixedly mounted on said standard in operative connection with said drive shaft, and a multiple-tub carrier rotatably mounted upon the lower portion of 100 said standard.

4. A washing machine comprising a central standard and relatively adjustable agitator and tub-supporting mechanism, a shaft-bearing bracket fixed to said standard, a horizontal drive shaft mounted on said bracket and having a projecting end portion provided with a worm gear and a swingable agitator arm on said bracket carrying agitator mechanism arranged in continuous engagement with said worm gear.

5. A washing machine comprising a central standard and relatively adjustable agitator and tub-supporting mechanisms, a shaft-bearing bracket fixed to said standard, a horizontal drive shaft mounted on said bracket and having a projecting end portion provided with a worm gear and a swingable agitator arm on said bracket carrying agitator mechanism arranged in continuous engagement with said worm gear.

gear, said bracket and agitator arm forming enclosing casings for the operating mechanism carried thereby.

6. A multiple-tub washing machine comprising a central standard having a fixed bearing bracket carrying a swingable agitator arm and agitator drive mechanism, a tub-carrying hub rotatably mounted on said standard and formed with a series of peripheral arm-engaging recesses, a series of

detachable tub-supporting bracket arms having recess-engaging projections and adapted to form rigid spoke extensions of said hub, and a movable arm-engaging catch adapted to hold any one of said rotatably adjustable arms in operative relation to the agitator. 15

In testimony whereof I affix my signature.

IRVIN D. LENGEL.
